UNITED STATES PATENT OFFICE.

CHARLES F. DOEBLER, OF AUSTIN, TEXAS, ASSIGNOR TO PERFECT POINT PENCIL CORPORATION, OF NEW YORK, N. Y., A CORPORATION OF DELAWARE.

RECHARGEABLE PENCIL.

Application filed June 30, 1921, Serial No. 481,466. Renewed October 20, 1928.

This invention relates to pencils. More specifically it relates to pencils of the type in which the lead or other crayon may be fed or forced from the body of the pencil.

5 One of the principal objects is to provide a simple though reliable feed mechanism.

Another object is to provide a pencil whose center of gravity is advantageously located. Other objects and advantages will appear as 10 the invention is hereinafter disclosed.

Referring to the drawings which illustrate what I now consider preferred forms of the invention,

Figure 1 is an elevation of a pencil embodying the invention.

Fig. 2 is a longitudinal section of the pencil shown in Fig. 1.

Fig. 3 is a view similar to Fig. 2 but illustrating a modification.

20 Referring to Figs. 1 and 2 it will be seen that the pencil there illustrated comprises a tubular body portion 10, externally threaded at its upper end to receive a cap 11, and provided at its lower end with a tip-receiving

25 bushing 12. The latter is shown in the form of an internally-threaded inverted cup whose external dimension is such that a tight fit between the casing and bushing is effected. If necessary or desirable the bushing 12 may

30 be soldered, brazed, welded or otherwise suitably secured to the casing 10. A conical tip member 13 is provided with an externally-threaded reduced portion 14 adapted to screw into the internally-threaded bushing 12. The

35 tip 13 is provided with an internal bore which is shown cylindrical above and conical below the line X—X, said bore being adapted to receive a cartridge of substantially the same exterior configuration as the bore of the tip

40 13. The cartridge 15 comprises a sheath and a lead or other crayon slidably mounted therein. The sheath is preferably constructed of wood, although other suitable material may be employed, and its bore is of such

45 design with respect to the diameter of the crayon that the crayon will not slip from its sheath except when propelled by a follower rod as will hereinafter be more fully explained. In short, the cartridge is of the

50 type disclosed in my copending application Serial No. 456,587. The upper end of the cartridge is preferably provided with a conical depression 17 adapted to receive or form a seat for a conical boss 18 struck from the

cup-shaped bushing 12. The boss 18 is provided with a hole through which a follower rod 19 is adapted to pass into the bore of the cartridge, the conical boss serving to guide the entrance of the rod into the bore of the cartridge. It will be apparent that movement of the rod 19 downwardly; i. e., toward the tip of the pencil, will cause the crayon 16 to feed from the pencil and that movement of the rod in the opposite direction will permit the crayon to be forced back into the pencil. While various forms of mechanism may be employed for actuating the follower rod 19, the form shown in Fig. 2 possesses marked advantages over those heretofore employed. This form may be constructed substantially 70 as follows:

The rod 19 is provided at its upper end with an externally-threaded collar 20 which is longitudinally movable but constrained against rotation, the longitudinal movement 75 being effected by means of an internally-threaded member 21. The rod 19 is provided with a right-angle-forming extension 21' adapted to enter a radial hole in the wall of the collar 20. The latter is internally bored to slide on a guide tube 22, secured to the casing 10 by means of a flange 23, the tube 22 being longitudinally slotted at 24 to permit longitudinal travel of the rod extension 21' and to prevent rotary movement of said 80 rod and collar 20 with respect to the casing 10. The rod 19 is provided with a bushing 25 which fits the rod tightly but is of such 85 external diameter as to travel freely in the tube 22 which guides its movement. It will be noted that the upper end of the bushing 25 is slotted to receive the rod extension 21'. The parts 19, 20 and 25 may be assembled as follows. The end 21' is inserted into the 90 radial opening in the collar 20. The bushing 25 is then forced up on the rod 19 until it assumes the position, with respect to the rod, illustrated in Fig. 2. The collar 20 may then be mounted on the tube 22, the bushing 25 entering the bore of the latter.

The member 21 is rotatable in the casing 10 but is constrained against longitudinal movement with respect thereto by means of the flange of the cap member 11, against which one end of said member 21 abuts, and the upper edge of the flange 23 against which the other end of said member abuts. As previously stated, the member 21 is internally-

threaded to cooperate with the threads on the collar 20, to operate the latter. A simple and inexpensive method of providing such threads consists in helically indenting the 5 wall of the sleeve 21 at its lower portion. A helical corrugation or thread is the result, as depicted in Fig. 2. The member 21 is preferably provided with an internal cup-shaped bushing 30 which cooperates with the upper 10 end of the tube 22 to form a bearing and, being secured to the sleeve 21, also serves to limit the travel of the screw 20 to prevent its disengagement from the tube 22 in the normal operation of the pencil.

15 For rotating the member 21 I provide a sleeve 31, the lower, reduced portion of which engages the interior of the member 21 with a friction fit so that rotation of the member 31 with respect to the casing 10 will cause rotation of the member 21. While not indispensable, I prefer to provide an ornamental head or knob 32 adapted frictionally to engage the upper, or enlarged, end of sleeve 31 whereby the latter and the member 21 may 20 be rotated by turning the head 32. A rubber or other eraser 33 is shown mounted in the lower end of the sleeve 31. The eraser is rendered available for use by removing the head 32 and sleeve 31 from the member 21. It 25 will also be noted that the cap member 11 has integrally secured thereto a garment-receiving clip 35 for the usual purpose. The assembly of the parts of the pencil will be readily understood by those skilled in the 30 art, in view of the foregoing disclosure. Its 35 operation may be described as follows.

If (with the parts in the position illustrated in Fig. 2) it is desired to feed the crayon 16 from the pencil the head 32 is turned in 40 the proper direction to rotate the sleeve 31 and member 21 to cause the collar 20 and the rod 19 to move downwardly. The crayon 16 is thereby forced from the bore of its sheath. Rotation of the head 32 in the opposite direction 45 will cause the follower rod 19 to move longitudinally in the opposite direction. When a crayon 16 has been completely consumed, the pencil may be recharged by unscrewing the tip 13 from the casing, removing 50 the used cartridge 15, inserting a fresh cartridge 15, rotating the head 32 to cause the rod 19 to reach its upper limit of travel, and screwing the cartridge-holding tip 13 into the bushing 12.

55 It will be noted that the upper portion of the member 21 may be employed for extra-crayon storage. And among other advantages it will be noted that I have provided a pencil in which the center of gravity is 60 much nearer the tip than is the case of the more or less top-heavy pencils now on the market. Fatigue in writing is thereby minimized. The device is comparatively simple, easy to manufacture and assemble, and durable though of light weight. It is, of course,

susceptible to modification. For example, the eraser 33 may be mounted in the upper part of the sleeve 31 (see Fig. 3) and rendered accessible by removing the head 32 from the sleeve 31. Or, the feed mechanism may be modified, one modification being illustrated in Fig. 3.

The majority of the elements shown in Fig. 3 will immediately be recognized in view of their similarity to those illustrated in Fig. 2, the same reference numerals being employed for corresponding parts. The threads on the member 21 are dispensed with and the member made in the form of a plain cylindrical tube. A helix 50 of comparatively stiff wire is provided with a bent-up end 51 which enters an opening in the base of the cup 30, thereby forming a connection between the member 21 and helix so that rotation of the member 21 with respect to the casing 10 will cause similar rotation of the helix. The latter co-operates with the threads on the collar 20 so that rotation of the helix causes longitudinal movement of the collar and the follower rod 19. The operation of the modified form of invention is otherwise the same as that of the form shown in Fig. 2.

Other modifications within the scope of the invention, as defined in the appended claims, will occur to those skilled in the art. To avoid surplusage I have not attempted to illustrate herein such further modifications.

What I claim is:—

1. In a pencil, the combination with a casing, of a rotatable head at one end thereof, a closure at the other end provided with a central opening, and a propelling mechanism in said casing comprising: a guide tube, means independent of said closure for holding said tube stationary, a follower rod movable longitudinally in said tube, means for guiding one end of said rod into said opening, an externally threaded collar secured to said rod and mounted on said tube for longitudinal movement thereon, means preventing rotation of said collar relatively to said tube, and a member surrounding said tube rotatable with said head and adapted to operatively engage said collar.

2. In a pencil, the combination with a casing, of a rotatable head at one end thereof, a tip at the other end, a cartridge in said tip provided with an axial bore, and a propelling mechanism comprising: a stationary guide tube, a follower rod movable longitudinally in said tube, means for guiding said rod in said tube, which means comprise a bushing at one end of said rod slidably fitting into said tube and means for guiding the other end of said rod into said axial bore, a collar secured to said rod and mounted on said tube for longitudinal movement relatively thereto, external threads on said collar, means preventing rotation of said collar relatively to said tube, and a threaded member sur-

- rounding said tube rotatable with said head and adapted to engage the threads of said collar.
3. In a pencil, the combination with a casing, of a rotatable head at one end thereof, a detachable tip at the other end, a removable cartridge in said tip provided with an axial bore, and a propelling mechanism in said casing comprising: a guide tube secured to said casing, a follower rod movable longitudinally in said tube, means for guiding said rod in said tube, which means comprise a bushing near one end of said rod slidably fitting into said tube and means for guiding the other end of said rod into said axial bore, a collar secured to said rod and mounted on said tube for longitudinal movement relatively thereto, external threads on said collar, means preventing rotation of said collar relatively to said tube, means limiting the longitudinal movement of said collar, a member adapted to engage the threads of said collar, and means connecting said member to said head to be rotated thereby.
25. In a pencil, the combination with a casing, of a rotatable head at one end thereof, a closure at the other end provided with a central opening, and a propelling mechanism in said casing comprising: a guide tube having a longitudinal slot, means independent of said closure to hold said tube stationary, a follower rod in said tube, means for guiding one end of said rod into said opening, an externally threaded collar on said tube mounted for longitudinal movement thereon, an extension of said rod secured to said collar and slidably in said slot, a spirally corrugated member surrounding said tube and adapted to operatively engage said collar, means connecting said corrugated member to said rotatable head to be rotated thereby, and means for preventing longitudinal movement of said corrugated member.
5. In a pencil, the combination with a casing, of a rotatable head at one end thereof, a bushing fitted into the other end of said casing, a propelling mechanism operated by said rotatable head and comprising a follower rod as one of its elements, a conical seat in said bushing provided with a central opening for guiding one end of said rod into said opening, and means disposed between said head and said bushing for securing said propelling mechanism in said casing.
55. In a pencil, the combination with a casing, of a rotatable head at one end thereof, a bushing fitted into the other end of said casing adapted to receive a tip provided with an axial bore, a conical seat in said bushing having a central opening registering with said bore, and a propelling mechanism in said casing operated by said rotatable head and comprising a follower rod and means for guiding one end of said rod into said opening.
7. In a pencil, the combination with a casing, of a rotatable head at one end thereof, a bushing fitted into the other end of said casing adapted to detachably receive a tip provided with an axial bore, a conical seat in said bushing having a central opening in registry with said bore, and a propelling mechanism in said casing comprising: a stationary guide tube, a follower rod in said tube movable longitudinally therein, means cooperating with said conical seat for guiding said rod into said opening, an externally threaded collar secured to said rod and mounted on said tube for longitudinal movement thereon, means for preventing rotation of said collar relatively to said casing, a member rotatable by said head surrounding said tube and adapted to operatively engage said collar, and means for preventing longitudinal movement of said member.
8. In a pencil, the combination with a casing, of a rotatable head at one end thereof, a tip at the other end and a propelling mechanism in said casing comprising: a guide tube, means independent of said tip for holding said tube stationary, a follower rod longitudinally movable therein, a threaded collar secured to said rod and longitudinally slideable on said guide tube, means preventing rotation of said collar relatively to said tube, and a member rotatable with said head and adapted to operatively engage said collar.
9. In a pencil, the combination with a casing, of a rotatable head at one end thereof, a detachable closure at the other end having a central opening, and a propelling mechanism in said casing comprising: a guide tube, means independent of said closure for securing said tube in said casing, a follower rod movable longitudinally in said tube, means for guiding said rod into said opening, an externally threaded collar secured to said rod and slideable on said tube, means preventing rotation of said collar relatively to said tube, and a member rotatable with said head and adapted to operatively engage said collar.
10. In a pencil, the combination with a casing, of a rotatable head at one end thereof, a detachable tip at the other end, a removable cartridge in said tip provided with an axial bore, and a propelling mechanism in said casing comprising: a stationary guide tube, a follower rod movable longitudinally in said tube, means for guiding said rod in said tube, which means comprise a bushing at one end of said rod slidably fitting into said tube and means for guiding the other end of said rod into said axial bore, a collar secured to said rod and slidably mounted on said tube, external threads on said collar, means preventing rotation of said collar relatively to said tube, and a threaded member rotatable with said head and adapted to engage the threads of said collar.
11. In a pencil, the combination with a cas-

ing, of a rotatable head at one end thereof, a tip at the other end provided with an axial bore, and a propelling mechanism in said casing comprising: a guide tube, means independent of said tip for holding said tube stationary, a follower rod longitudinally movable in said tube, means for guiding said rod in said tube and into said axial bore, a collar secured to said rod and slidably mounted on said tube, means preventing rotation of said collar relatively to said tube, and a member rotatable with said head and adapted to engage said collar.

12. In a pencil, the combination with a casing, of a rotatable head at one end thereof, a closure at the other end having a central opening, a propelling mechanism operated by said rotatable head and including a follower rod as one of its elements, means independent of said closure for securing said propelling mechanism in said casing, and means for guiding said follower rod into said central opening. 15
20

In testimony whereof I hereto affix my signature.

CHARLES F. DOEBLER.
